Peter W. Reardon

UNITED STATES PATENT OFFICE.

JAMES A. BROGAN, OF LAWRENCE, MASSACHUSETTS, ASSIGNOR TO UNITED SHOE MACHINERY CORPORATION, OF PATERSON, NEW JERSEY, A CORPORATION OF NEW JERSEY.

OVERFLOW-TRIMMING MACHINE.

Application filed October 12, 1921. Serial No. 507,195.

To all whom it may concern:

Be it known that I, JAMES A. BROGAN, a citizen of the United States, and resident of Lawrence, in the county of Essex and Commonwealth of Massachusetts, have invented certain Improvements in Overflow-Trimming Machines, of which the following description, in connection with the accompanying drawings, is a specification, like reference characters on the drawings indicating like parts in the several figures.

This invention relates to cutting machines and is herein illustrated as embodied in a machine for trimming the overflow from molded rubber heels.

Such heels are made by placing blanks of unvulcanized rubber or rubber compound in molds and subjecting them to heat and pressure. During the subjection of the blanks to heat and pressure more or less of the rubber flows into the spaces between the parts of the mold so that the vulcanized heels have fins or lips which result from this overflow and must be trimmed off before the heels are incorporated in boots or shoes.

A type of rubber heel which has gone into wide use comparatively recently is concave on the heel seat face and convex on the tread face, the heel as a whole being thus concavo-convex; and the variously curved edges and faces which are present in such a heel have introduced difficulties into the overflow trimming operation.

The general object of the present invention is to provide an improved trimming machine which is suitable for operating upon this and other types of rubber heels and similar articles.

According to one feature of the invention, in the illustrated construction a pair of co-operating shear cutters are provided in combination with a work support one edge of which lies close to the locality in which the cutters meet, and in front of that cutter which is above the work support extends a thin-edged guard which is preferably a hollow rotatable one extending over the cutter. With this construction the shear cutters may be caused to sever the overflow from any type of heel by a clean cut which is substantially flush with the edge face of the heel from which the overflow projects, the construction being particularly advan-

tageous when concavo-convex heels, which often must be swung on short radii, are encountered, since the operator may hold an edge face of the heel against the guard, while feeding the heel, and swing the heel as may be required without danger of injury either to his fingers or to the work.

If the work support is at a proper height to present the overflow on the concave face of a heel of the concavo-convex type to the bite of the cutters and then the heel is turned over on its convex face, it will be obvious that the overflow on that face will be located partly or wholly above the bite of the cutters; and the same difficulty may be caused or increased by projections on one of the faces of a heel such, for example, as the raised rings which commonly encircle the nail holes on the tread faces of concavo-convex heels as well as heels otherwise substantially flat on their tread faces. According to another feature of the invention the work support is so mounted that it may be raised and lowered, and means are provided under the control of the operator for so raising and lowering it at will during the operation of the machine. Thus, while the operator guides the heel to the cutters, he may, as is necessary or desirable, raise or lower the work support during the operation of the machine so as to sever the overflow exactly in line with the sides or breast of the heel.

In presenting the heel to the cutters and in feeding it to them, it is desirable in many cases that a portion of the heel which is not being operated upon be moved above or maintained above the periphery of the lower cutter. In order to prevent this portion of the heel from being accidentally cut, as well as to aid the operator in presenting and feeding the heel, another feature of the invention comprises a member extending above the periphery of the lower cutter in position to be engaged by the under side of the work before the work is operated upon by the cutters.

Other features of the invention comprise means for supplying lubricant to that surface of the guard for the upper cutter which engages the work and a work support of special shape.

These and other features of the invention, including certain details of construction and

combinations of parts, will be described as embodied in an illustrative machine and pointed out in the appended claims.

Referring now to the accompanying drawings,—

Fig. 1 is a perspective of a machine in which the present invention is embodied.

Fig. 2 is a vertical section through the forward portion of the machine, certain parts being shown in full lines;

Fig. 3 is a perspective showing the machine trimming the overflow from the concave face of a heel, and

Fig. 4 is a similar view with the heel turned over.

Mounted in the frame 5 of the machine is a driving shaft 7 which may be rotated by power applied to a pulley 9, said shaft having fast to its outer end an upper cutter 11 of small diameter arranged to co-operate so as to produce a shear cut with a larger cutter 13 which is fast to the outer end of a shaft 15. Fast to the inner end of the shaft 15 is a gear 17 which meshes with a pinion 19 on the drive shaft 7 so that both cutters are positively driven at approximately the same peripheral velocity.

Located in front of the cutters is a work support or table 19 fastened to bars 21, 23 each bar carrying a trunnion in the form of a small rod, the one carried by the bar 21 being indicated at 25. The trunnion which is carried by the bar 23 is a similar rod and passes loosely through a bore in the upper end of a standard 27 so that the opposite trunnion 25, and with it the bar 21 and the table 19, may be raised and lowered. The trunnions are alined and their axis is transverse to the axes of the cutters and passes substantially through the locality in which the cutters meet. The weight of the table tends at all times to cause it to swing downwardly; and the extent of this downward movement is limited by contact of a bar 29, which is fast to the table, with a stud 31, said stud having a threaded stem of reduced diameter passing through a vertical slot in a stationary upright member 33 and being held in adjusted position by a nut 35.

In order to provide for the raising and lowering of the trunnion 25 and with it the table 19, said trunnion passes through a bore in a member 37 which is vertically slideable in a guideway in a guide member 39, said guide member being mounted for vertical adjustment on a standard 41. The guide member 39 is held in adjusted position by a wing-nut 43 threaded upon a stud which passes through a vertical slot in the guide member and is carried by the standard 41. The slide member 37 is normally held in the position shown with respect to the guide member 39 by a tension spring 45 fast at its upper end to a pin 47 carried by the slide member and at its lower end to a pin 49.

carried by the guide member 39 and passing through a vertical slot in the slide member. A lever 51 pivoted at 53 to the guide member 39 is forked at one end to receive the pin 47. With this construction, when the wing-nut 43 has been loosened, the guide member 39 with its associated parts may be raised or lowered to bring the trunnion 25 and with it the table 19 into the desired normal position, after which the wing-nut is tightened. Thereafter, by pressing down upon the free end of the lever 51, the table may be raised against the tension of the spring 45, and thereafter, when the pressure upon the free end is diminished or removed, the table will be lowered to its normal position as determined by the vertical position of the guide member 39.

The table is cut away in two localities on the side toward the cutters to form a narrow projection 54 so that when a concavely curved edge of the heel, such as the breast edge, is encountered the heel may be rocked on the projection and the overflow properly presented to the cutters. The sides of the projection may be beveled, as shown, if desired. In order to facilitate the feeding of the work, a series of idle rolls 56 are mounted in the table opposite the bite of the cutters.

It is essential in machines of this type that no cutting into the heel itself shall occur. In order to prevent the upper cutter from doing this, a guard is provided having a portion extending in front of said cutter. As illustrated this guard is shown as a hollow conical thin-edged member 55 which extends over the cutter in such manner as to leave exposed only a small portion of the lower part of the cutter. This hollow guard, in the illustrative machine, also aids in feeding the work and to that end is carried at the lower end of a spindle the upper end of which carries a spiral gear 55 which meshes with a spiral gear 57 cut on the end of a short shaft 59. The inner end of this shaft carries a large gear 61 which is driven through an idle gear 63 by a gear 65 fast to the driving shaft 7. The spindle of the hollow guard 55 is inclined from top to bottom toward the rear of the machine as shown so that the forward portion of the guard lies close to the front face of the upper cutter. The bracket 67, which carries the hollow guard and the short shaft 59 is adjustable in a direction parallel to the axis of the driving shaft 7 and is held in adjusted position by a screw bolt 69 which passes through a slot in the frame of the machine and is threaded into the bracket. It is thus possible to adjust the guard toward and from the face of the cutter 11.

In order to lessen the friction between the guard and the work means are provided for supplying lubricant to the work-engaging face of the guard. As shown, a pipe 71

leads from a receptacle 73, formed in the upper part of the frame of the machine, to a point in proximity to the outer surface of the guard and carries in its end a piece of bibulous material 75 such as felt which it holds in contact with the guard.

In feeding a heel to the machine a portion of the heel, at a locality which has not yet been operated upon by the cutters, is maintained over the periphery of the lower cutter, such a position being advantageous in trimming the curved edges of the heel. In order to prevent the lower cutter from coming into contact with the under side of the heel, as well as to aid in positioning the heel during the operation of the machine, there is provided a guard 77 which extends above the periphery of the lower cutter at a locality in advance of that in which the cutters engage the work. This guard has a curved upper portion and is carried by a stem 79 having a threaded lower end of reduced diameter. A thumb-nut 81, threaded on the reduced portion of the stem and held from movement in the direction of extent of the stem provides means for adjusting the guard vertically.

In the operation of the machine the heel, assuming it to be of the concavo-convex type, may be presented first with the concave face resting upon the table as shown in Fig. 3 and trimmed all the way around and then turned over as shown in Fig. 4 and again trimmed all the way around. If there is still left a fin or a remnant of a fin along one or both edges of the breast which will often be the case with one type of heel in common use, the rear end of the heel may be raised, and the breast edge or edges trimmed more closely by rocking the heel about the projection 54. During the trimming operation the handle 51 may be manipulated, when desired, to change the height of the table.

Although the invention has been set forth as embodied in a particular machine, it should be understood that the invention is not limited in the scope of its application to the particular machine which has been shown and described.

Having thus described my invention, what I claim as new and desire to secure by Letters Patent of the United States is:

1. A machine for trimming a fin from a molded rubber article having, in combination, a rotary cutter, a cooperating shear member, a thin-edged guard having its work-engaging portion extending in front of the cutter whereby a face of the article may be held against the guard and the article so fed as to cause the fin to be severed substantially flush with said face, and means whereby the guard may be adjusted toward and from the cutter.

2. A machine for trimming a fin from a molded rubber article having, in combina-

tion, a rotary cutter, a cooperating rotary shear member, and a thin-edged rotatable guard having its work-engaging portion extending in front of the cutter and located close to said cutter whereby a face of the article may be held against the guard and so fed as to cause the fin to be severed substantially flush with said face.

3. A machine for trimming a fin from a molded rubber article having, in combination, a pair of cooperating rotary shear cutters, a thin-edged rotatable guard having its work-engaging portion extending in front of one of the cutters and located close to said cutter, and a work support extending close to the bite of the cutters whereby the article may be placed upon the work support with a face held against the guard and so fed as to cause the fin to be severed substantially flush with said face.

4. A machine for trimming a fin from a molded rubber article having, in combination, a pair of cooperating rotary shear cutters, a thin-edged rotatable guard having its work-engaging portion extending in front of one of the cutters and located close to said cutter, a work support extending close to the bite of the cutters whereby the article may be placed upon the work support with a face held against the guard and so fed as to cause the fin to be severed substantially flush with said face, and means for rotating the guard to facilitate feeding the article.

5. A machine for trimming a fin from a molded rubber article having, in combination, a pair of cooperating rotary shear cutters, a work support adapted to support the article with the fin projecting beyond the plane of the cutters, and a thin-edged, hollow, rotatable guard extending over one of the cutters and having its operative, article-engaging portion located close to said cutter, whereby a face of the article may be held against the guard and the article moved so as to cause the fin to be severed close to the edge of said face.

6. A machine for trimming a fin from a molded rubber article having, in combination, a pair of cooperating rotary shear cutters, a work support angularly adjustable about an axis lying close to the bite of the cutters adapted to support the article with the fin projecting beyond the plane of the cutters, and a thin-edged, hollow, rotatable guard extending over one of the cutters and having its operative, article-engaging portion located close to said cutter, whereby a face of the article may be held against the guard and the article moved so as to cause the fin to be severed close to the edge of said face.

7. A machine for trimming a fin from a molded rubber article having, in combination, a pair of cooperating rotary disk

shear cutters located one above the other, a work support angularly adjustable about an axis lying close to the bite of the cutters adapted to support the article in inclined position with the fin projecting past the plane of the cutters, a thin-edged, hollow, rotatable guard extending over the upper cutter and having its operative heel-engaging portion located close to said cutter and means for rotating the guard, whereby a face of the article may be held against said guard and the article so moved as to cause the fin to be severed close to the edge of said face.

15. 8. A machine for trimming the overflow from a molded-rubber heel, the tread face of which has a portion lying at a different level from that of the overflow which projects from said face comprising a pair 20 of co-operating shear cutters, an angularly adjustable work support for the heel, and means for raising and lowering the work support bodily during the trimming operation to maintain the overflow of the heel 25 at a proper level to be engaged by the cutters.

9. A machine of the class described, having in combination, a pair of co-operating shear cutters, means for operating the cutters, a work support angularly adjustable about an axis extending at an angle to the axes of the cutters and passing substantially through the locality in which the peripheries of the cutters meet, and means whereby the work support may be raised and lowered during the operation of the machine.

10. A machine of the class described, having in combination, a pair of rotatable cutters, means for rotating the cutters, a work support in front of the cutters angularly adjustable about an axis transverse to the axes of the cutters, yielding means for holding the axis normally substantially horizontal, and means under control of the operator during the operation of the machine for raising one end of the axis.

11. A machine of the class described, having in combination, a pair of rotatable cutters, means for rotating the cutters, a work support in front of the cutters, alined rods upon which the work support is mounted, standards by which the rods are sustained, one rod being loosely mounted in one standard, a slide member carrying the other rod and mounted in the other standard, yielding means for holding the slide member in a given position, and means under control of the operator during the operation of the machine for raising the slide member.

12. A machine for trimming a fin from a molded rubber article having, in combination, a rotary cutter, a work support, a hollow rotatable guard extending over the cutter in position to engage an edge of an

article which rests upon the work support, means for rotating the guard to facilitate feeding the article, and means for supplying lubricant to the work-engaging face of the guard to modify its feeding action. 70

13. A machine of the class described, having in combination, a pair of co-operating rotatable cutters located one above the other, means for rotating the cutters, a downwardly inclined work support in front of the cutters, a guard for the upper cutter and a guard for the lower cutter, said last-named guard extending above the periphery of the lower cutter in position to be engaged by the under side of the work before the work is 80 operated upon by the cutters.

14. A machine of the class described, having in combination, a pair of co-operating rotatable cutters located one above the other, means for rotating the cutters, a downwardly inclined work support in front of the cutters, a hollow, rotatable guard extending over the upper cutter, and a guard for the lower cutter, said last-named guard extending above the periphery of said lower cutter on that side of the meeting point of the cutters from which the on-coming work approaches. 85

15. A machine of the class described, having in combination, a pair of co-operating rotatable cutters located one above the other, means for rotating the cutters, a downwardly inclined work support in front of the cutters, a hollow, rotatable guard extending over the upper cutter, and a member extending above the periphery of the lower cutter in position to engage the lower side of the on-coming work before it reaches the co-operating portions of the cutters. 90

16. A machine of the class described, having in combination, a pair of co-operating rotatable cutters located one above the other, means for rotating the cutters, a downwardly inclined work support in front of the cutters, a hollow, rotatable guard extending over the upper cutter, and a member extending above the periphery of the lower cutter in position to engage the lower side of the on-coming work before it reaches the co-operating portions of the cutters, said member 100 being mounted for vertical adjustment. 105

17. A machine of the class described, having in combination, a pair of co-operating rotatable cutters located one above the other, means for rotating the cutters, a downwardly inclined work support in front of the cutters, a hollow, rotatable guard extending over the upper cutter, and a guard for the lower cutter, said last-named guard extending above the periphery of said lower cutter 110 in position to be engaged by the work before the work is operated upon by the cutters. 115

18. A machine of the class described, having in combination, a pair of co-operating cutters, means for operating the cutters, an 120

- angularly adjustable table provided with a narrow projection adjacent to the locality in which the cutters meet, and a roller carried by the table adjacent to the projection.
- 5 19. A machine for trimming the overflow from a molded rubber heel having a convex face and a concave face comprising a pair of co-operating shear cutters, an angularly adjustable work support for the heel, and
- 10 means for moving the work support during the trimming operation in such manner as to raise and lower the heel bodily.
- 20 20. A machine for trimming the overflow from a rubber heel having a convex
- face and a concave face, comprising a work support the greater portion of which is substantially flat upon which either face of the heel may rest, a cutter arranged to operate near one locality in the edge of the support, and means for changing the position of that locality with respect to the cutter so as to sever the overflow properly whether the concave or convex face of the heel rests upon the support.

In testimony whereof I have signed my name to this specification.

JAMES A. BROGAN.
